CLAIM

I claim the ornamental design for a pet car seat, as shown and described.

DESCRIPTION

FIG. 1 is a perspective view of a pet car seat showing my new design;

FIG. 2 is a front elevational view thereof;

FIG. 3 is a top plan view thereof;

FIG. 4 is a left side elevational view thereof;

FIG. 5 is a rear elevational view thereof;

FIG. 6 is a right side elevational view thereof; and,

FIG. 7 is a bottom plan view thereof.

The broken lines shown in the figures are for the purpose of illustrating portions of the pet car seat, which form no part of the claimed design.
